UNITED STATES PATENT OFFICE.

RUBY LEFI, OF NEW YORK, N. Y.

DESIGN FOR A STOCKING.

Application filed October 14, 1927. Serial No. 23,751. Term of patent 14 years.

To all whom it may concern:

Be it known that I, RUBY LEFI, a citizen of the United States, and a resident of the city of New York, borough of Manhattan, in the county of New York and State of New York, have invented the new, original, and ornamental Design for a Stocking, of which the following is a specification.

Reference is had to the accompanying drawing, forming part thereof, wherein

I claim:

The ornamental design for a stocking, substantially as shown.

Signed at New York in the county of New York and State of New York this 13th day of October, A. D. 1927.

RUBY LEFI.
